UNITED STATES PATENT OFFICE.

RICHARD H. BARBER, OF RICH HILL, MISSOURI, ASSIGNOR OF ONE-THIRD
TO ROBERT INNIS, OF SAME PLACE.

LATCH.

SPECIFICATION forming part of Letters Patent No. 406,019, dated July 2, 1889.

Application filed February 12, 1889. Serial No. 299,630. (No model.)

To all whom it may concern:

Be it known that I, RICHARD H. BARBER, a citizen of the United States, residing at Rich Hill, in the county of Bates and State of Missouri, have invented new and useful Improvements in Locks for Doors and Windows, of which the following is a specification.

The invention relates to improvements in locks for doors and windows; and it consists in a certain novel construction and combination of parts, fully described hereinafter, in connection with the accompanying drawings, and specifically pointed out in the appended claims.

15 In the drawings, Figure 1 is a view of the improved lock applied in the operative position to a door. Fig. 2 is a similar view, partly in section. Fig. 3 is a detail view of the door-plate. Fig. 4 is a similar view of 20 the frame-plate. Fig. 5 is a similar view of the latch. Fig. 6 is a transverse section on the line $x-x$, Fig. 2. Fig. 7 is a detail in perspective of the locking turn-buckle.

25 Referring by letter to the drawings, A designates a door having a recess a in its free edge, over which is arranged the door-plate B, having a vertical slot C, and D designates the frame of the door, which is also provided with a recess E, covered by a frame-plate F. 30 This frame-plate is provided with a flange G, which fits against the edge of the frame and faces the edge of the door, and the said flange is provided with a vertical slot H, which registers with the slot in the door-plate when the door is in its closed position.

35 The latch K consists of a rock-shaft L, which is mounted in a bearing X in the frame-plate, and is provided at its inner end with a laterally-projecting tongue M, which 40 is adapted, when the rock-shaft is turned, to swing through the slot in the flanges of the frame-plate and engage the slot in the door-plate. This shaft is provided at its outer end with a knob N, which is elongated in direction parallel with the length of the swinging tongue, whereby, when the door is unlocked, the longer diameter of the knob is

vertical, and when the door is locked the longer diameter thereof is horizontal.

Pivoted secured by a screw O' to the frame 50 of the door, and immediately below and in a vertical line with the rock-shaft L, is a turn-button O. The button O consists of a metal plate having a longitudinal rib O². Below the end of the rib O² is formed a screw-opening O⁵, through which the screw O' above referred to is passed. The relative location of this button is such that it can only be 55 swung to a vertical position when the door is locked; or, in other words, when the knob 60 N is in a horizontal position, and when so arranged the terminals of the plate bear upwardly against the knob, thus preventing the rotation or unlocking of the shaft L. From the above the object of elongating the knob 65 is apparent.

The advantages of the improved lock are that it cannot be picked from the outside of the door. It is readily operated from the inner side of the door. It is simple and may 70 be cheaply manufactured, and it is readily applied to the door without marring the surface thereof.

Having thus described the invention, I claim—

1. The combination, with the door-plate B, vertically slotted, as at C, and attached to the edge of a door, of the frame-plate F, secured to the frame of the door, and provided with a flange G, having a slot H, which registers with the slot in the door-plate, and provided with the bearing X, arranged at an angle to the slot, and the rock-shaft mounted in the bearing in the frame-plate and provided with a laterally-projecting swinging 85 tongue to engage the said registering slots, substantially as specified.

2. The combination, with a vertically-slotted door-plate affixed to the edge of a door and the flanged and slotted frame-plate affixed to the frame, of the rock-shaft provided with a tongue to engage the slots in the said plates, and the elongated knob affixed to the outer end of the rock-shaft and having its

longer diameter parallel with the length of the tongue, substantially as specified.

3. The combination, with a vertically-slotted door-plate affixed to the edge of the door and the slotted frame-plate, of the rock-shaft provided with a tongue to engage the slotted plate and an elongated knob, and the turn-button O, to engage the said knob, substantially as specified.

In testimony that I claim the foregoing as 10 my own I have hereto affixed my signature in presence of two witnesses.

RICHARD H. BARBER.
